REFRIGERATING APPARATUS

Robert R. Candor, Dayton, Ohio, assignor to General Motors Corporation, Dayton, Ohio, a corporation of Delaware

Application February 4, 1935, Serial No. 4,834

3 Claims. (Cl. 62—3)

This invention relates to refrigerating apparatus and more particularly to a novel system and control therefor for automatically varying the refrigeration output of the apparatus.

- 5 Heretofore, in the construction of refrigerators, particularly those comprising a cabinet having a food storage compartment and which are intended principally for household use, in meeting the problem of varying the refrigeration output of the machine to provide substantially constant food preserving temperatures in the cabinet, it has been customary to provide an automatic switch for stopping and starting the refrigerant liquefying unit as by controlling the motor which 10 drives the compressor and to thus operate the apparatus intermittently. With such a method of control, the system, while it is operating, produces refrigeration at a substantially constant rate and the variation in average amount of refrigerant produced over a given period results 15 in variations in the lengths of the period during which the machine operates or is idle. A refrigerating apparatus of this character has certain disadvantages, among them being high first cost 20 and frequent service difficulties, together with certain difficulties arising from the continued stopping and starting of the refrigerant liquefying unit, particularly with liquefying units of the compression type.
- 25 It is an object, therefore, of the present invention to provide a refrigerating apparatus which is readily adapted to extremely low cost production and in which the difficulties inherent in an intermittently operated refrigerator are avoided.

30 It is a further object of the invention to provide a refrigerating apparatus in which automatic control of the output of the apparatus is attained while the refrigerant liquefying unit is constantly running.

35 It is also an object of the invention to provide a refrigerating apparatus in which the liquefying unit runs continuously throughout a substantial range of room temperatures normally encountered and in which substantially constant temperatures are maintained in the food preserving or other compartment to be cooled solely by controlling the rate of withdrawal of vaporized refrigerant from the evaporator, and to avoid losses 40 which may otherwise be present in such a system of control.

45 Further objects and advantages of the present invention will be apparent from the following description, reference being had to the accompany-

ing drawing, wherein a preferred form of the present invention is clearly shown.

In the drawing:

5 Referring now to the drawing, the figure illustrates a diagrammatic view of a refrigerating apparatus embodying the present invention, a portion of the mechanism being shown in cross section.

10 In the form of the invention illustrated in the figure, there is provided a refrigerator cabinet indicated diagrammatically at 10 forming a food compartment 12 in which substantially constant temperatures are to be maintained throughout a wide range of room temperatures. For example, in an ordinary household refrigerator, it is desirable to maintain a temperature within the compartment 12 between substantially 42° and 50° F., while room temperatures may run as high as 110° and are generally not below 60° F. Associated with the cabinet 10 is a refrigerant liquefying unit comprising a compressor 14 mounted with a motor 15 in a sealed housing 17, and a condenser 16, all of which may take any of numerous suitable forms in order to maintain 15 a constant supply of liquefied refrigerant for use 20 in the system. Within the compartment 12, there is mounted a refrigerant evaporator 18 for for cooling the air within the compartment 12, and which may also be provided with means for freezing water as is well known in the art. Suitable 25 means for controlling the flow of liquid refrigerant from the liquefying unit to the evaporator are provided and may comprise a fixed restrictor or other refrigerant control device 20. The elements so far described are connected in 30 series by suitable refrigerant conduits in the well known manner to provide a closed refrigerant circuit. The elements of the refrigerating system including the refrigerant liquefying unit, 35 the liquid refrigerant control device and the evaporator are preferably so proportioned and co-ordinated with each other as to provide a maximum refrigeration output not substantially in excess of the heat load requirements of the cabinet 40 under the highest room temperature normally encountered.

45 In order to provide for a reduction in the output of the apparatus under conditions at which the maximum output is too great for maintaining proper temperatures within the compartment 12, a thermostatically controlled valve 22 is provided in the refrigerant conduit between the evaporator 18 and the compressor 14. The valve 22 comprises a housing 24 formed with a valve 50

- seat 26 adapted to be opened and closed by a valve 28. The valve 28 is moved between open and closed positions by a bellows 30 acting through a push rod 32, a diaphragm 33 and a yoke 35. 5 The bellows 30 is connected to a thermostatic bulb 34 located in the compartment 12 and when suitably charged with a volatile liquid, acts to open and close the valve 28 in accordance with temperature conditions within the compartment 10 12. In order to prevent a loss otherwise entailed in the reduction of pressure and consequent expansion of the refrigerant passing through the thermostatic valve 22, a heat interchanger 36 is provided in the conduit connecting the valve 22 15 with the compressor 14. This causes the refrigerant expanding from the valve 22 to withdraw heat from the liquid refrigerant entering the restrictor 20.
- In operation of the apparatus, whenever current is fed to the motor 15, the refrigerant liquefying unit comprising the motor 15, compressor 14 and condenser 16 will remain in operation regardless of the load requirements of the evaporator 18. Refrigerant is compressed in the compressor 14 and delivered to the condenser 16 where it is condensed to be expanded through the restrictor 20 and vaporized in the evaporator 18. The vaporized refrigerant is withdrawn from the evaporator 18 through the valve 22 to be returned to the compressor 14 for recompression. When the temperature within the compartment 12 is above the maximum desirable temperature, the thermostatic valve 22 is maintained open by the pressure in the bellows 30, permitting refrigeration to take place at the maximum rate of which the system is capable. As soon as the withdrawal of heat from the air in the compartment 12 by the evaporator 18 has reduced the temperature of the air sufficiently to bring it 30 within the desired range, the bellows 30 begins to contract and to close the valve 22. Thereafter, the withdrawal of vaporized refrigerant from the evaporator 18 is decreased until such time as the valve 22 again opens. It will be noted that 35 the refrigerant liquefying unit is maintained in continuous operation and that the temperature of the air in compartment 12 is maintained substantially constant notwithstanding the continuous operation of the refrigerant liquefying unit. 40 By this construction, it is possible to provide a refrigerating apparatus wherein the refrigerant liquefying unit runs continuously throughout substantially the entire range of room temperatures normally encountered, although if a 45 thermostatic switch is provided for controlling the motor-compressor 14, its cut-out point may be selected so as to provide intermittent operation of the liquefying unit below any desired room temperature less than maximum. The efficiency of the apparatus while operating at reduced load is maintained by the operation of 50 the heat interchanger 36 which causes the refrigerant

erant expanding from the valve 22 to absorb heat from the warm liquid refrigerant entering the restrictor 20.

Thus, the present invention provides a refrigerating apparatus having means for maintaining the temperature of the compartment to be cooled within a predetermined range, while the refrigerating apparatus for the compartment is maintained in continuous operation. 5

While the form of embodiment of the present invention as herein disclosed constitutes a preferred form, it is to be understood that other forms might be adopted, all coming within the scope of the claims which follow.

What is claimed is as follows:

1. A unitary household refrigerating apparatus comprising a cabinet to be cooled, a refrigerant liquefying unit, an evaporator in heat exchange relation to the air in said cabinet, a fixed orifice restrictor between said liquefying unit and evaporator, thermostatic means for controlling the entire flow of refrigerant from the evaporator to the liquefying unit to vary the amount of refrigeration produced by said apparatus while maintaining said liquefying unit in operation 25 whereby to maintain substantially constant temperatures in said cabinet, and a heat interchanger for exchanging heat between the cold gas leaving said thermostatic means and the liquid refrigerant leaving the liquefying unit. 30

2. A unitary household refrigerating apparatus comprising a cabinet to be cooled, a refrigerant liquefying unit, an evaporator in heat exchange relation to the air in said cabinet, a fixed orifice restrictor between said liquefying unit and evaporator, thermostatic means including a valve for controlling the entire flow of refrigerant from the evaporator to the liquefying unit to vary the amount of refrigeration produced by said apparatus while maintaining said liquefying unit in operation whereby to maintain substantially constant temperatures in said cabinet, and a heat interchanger for exchanging heat between the cold gas leaving said thermostatic valve means and the liquid refrigerant leaving the liquefying unit. 45

3. Refrigerating apparatus comprising, means forming a space to be refrigerated, an evaporator in heat exchange relation to the air to be cooled 50 for said space, a refrigerant liquefying unit, a fixed orifice restrictor between said liquefying unit and evaporator, an evaporated refrigerant line between said evaporator and liquefying unit, heat exchange means between liquid refrigerant 55 flowing between said liquefying unit and restrictor with refrigerant flowing from said evaporator to said liquefying unit, and a thermostatically controlled throttling valve in said evaporated refrigerant line between said evaporator and 60 said heat exchanger.
